UNITED STATES PATENT OFFICE.

JOHN A. PRINCE, OF NEW YORK, N. Y.

BOTTLE-WASHING MACHINE.

981,002.

Specification of Letters Patent. Patented Jan. 10, 1911.

Application filed April 4, 1910. Serial No. 553,296.

To all whom it may concern:

Be it known that I, JOHN A. PRINCE, a citizen of the United States, residing at New York city, county and State of New York, have invented new and useful Improvements in Bottle-Washing Machines, of which the following is a specification.

This invention relates to a machine of novel construction for cleaning bottles on the exterior and interior in a quick and reliable manner, and has, more particularly, for its object to increase the efficiency of a similar machine patented to me on December 6, 1904, under No. 776,547.

15 In the accompanying drawings: Figure 1 is a side elevation of my improved bottle washing machine; Fig. 2 a detail of part of the soaking drums; Fig. 3 a right hand side elevation of the scrubbing mechanism; Fig. 20 4 a left hand side elevation thereof; Fig. 5 a longitudinal section through an internal brush and coöperating parts; Fig. 6 a detail of part of the brush reciprocating means; Fig. 7 a detail of the roller actuating means; Fig. 8 a detail of one of the cams for oscillating the internal brushes; Fig. 9 a detail of one of the bottom brushes; Fig. 10 a detail of the drum-piping; Fig. 11 a detail of the cam shaft; Fig. 12 a detail of the rollers and coöperating parts, and Fig. 13 a detail of the means for actuating the inner brushes.

The machine comprises essentially a plurality of soaking drums which automatically 35 deliver the soaked bottles to means for interiorly and exteriorly scrubbing the same. The drums are substantially of the same construction as those shown in Patent No. 738,937, granted to me September 15, 1903. 40 Each of these drums is divided by longitudinal and transverse partitions into a number of compartments or pockets, which are closed at their inner ends by cylindrical perforated walls. These drums dip with 45 their lower sections into curved tanks or troughs arranged concentric to the drums and directly beneath the same, so as to support the bottles contained within the immersed pockets.

50 The drawing shows three drums 15, 16, 17, dipping into tanks 18, 19, 20, respectively. Tank 18 is preferably filled with a solvent, such as a soda solution which is introduced into the tank through a pipe 21 controlled by valve 22. Into this pipe, steam may be admitted through a pipe 23

controlled by valve 24, which serves to heat the solution if desired. The tank may be emptied through a discharge pipe 25 having valve 26. Tanks 19, and 20, contain preferably pure water introduced through pipes 27, 28, provided with valves 29, 30, while outlet pipes 31 serve for emptying the tanks. The water entering tanks 19, 20 may be heated by steam admitted into pipe 27 through conduit 32 controlled by valve 33. Suitable overflow pipes 34, 35, 36 take care of the surplusage of liquid after the tanks have been filled to the desired level.

Drums 15, 16, 17 receive rotation from a counter-shaft 37, hereinafter referred to, through a chain 38 and beveled gear wheels 39. One of said wheels is secured to a shaft 40 mounted in bearings 41 and carrying a worm 42 that meshes into a gear wheel 43 secured to the axis of drum 17. Wheel 43 drives a train of toothed wheels 44, 45, 46, 47, of which wheels 45, 47 are secured to the shafts of drums 16, 15, respectively.

It will be seen that by the mechanism described, the several drums are simultaneously rotated in the same direction. The bottles, inserted into the pockets of drum 15, are thereby gradually lowered and drawn through the solvent, while their interior becomes filled with such solvent. After the filled bottles have ascended beyond the liquid level of tank 16, the solvent will run out of the bottles and the bottles thus emptied will, by gravity, slip out of the drum 15 and into drum 16, to be subsequently drawn through and filled with the clean water contained in tank 19. Finally, the bottles are transferred to drum 17 to be again immersed into and drawn through 90 fresh water, as will be readily understood. After the bottles have thus been thoroughly soaked and emptied, they slip out of drum 17 and over an inclined guard 48, to be delivered upon rollers 49. These rollers are 95 hung in a frame 50 and receive continuous rotary motion from a power shaft 51 through chain 52, transverse shaft 53 and beveled gear wheels 54.

In order to feed the bottles along rollers 105 49, there are provided between each pair of such rollers, a pair of rotating arms 55, 56, carrying brushes 57 which are adapted to engage the bottle bottoms. Arms 55, 56 are secured to transverse shafts 58, 59 connected 110 by a chain 60 and receiving intermittent rotary motion in the following manner:

The main shaft 51 of the machine, which receives rotation through a belt 61, is, by chain 62, connected to counter-shaft 37. To the latter is keyed a gear wheel 63 meshing into a similar wheel 64 secured to a transverse shaft 65, which transmits intermittent rotary movement to shaft 57 by mutilated gear wheels 66, 67 and chain 68. During their forward movement along revolving rollers 49, the bottles are subjected to the action of a first scrubbing brush 70 that receives continuous rotary movement from shaft 53 by chain 71. Brush 70 is hung in arms 72 which are loosely mounted on a transverse shaft 73 journaled in standards 74. Arms 72 may be adjustably clamped to slotted brackets 75, so as to adapt the machine to bottles of various thicknesses.

In order to insure a positive rotation of the bottles while cleaning the interior thereof, there is provided above each roller 49 a pressure roller 76. Rollers 76 are hung in bearings 77 which are yieldingly mounted in cross bars 78 supported by standards 74, 79, respectively. Intermediate each pair of adjoining rollers 76, a brush 80 is secured to a transverse shaft 81 which is hung in arms 82 fastened to shaft 73 and receives rotary movement from shaft 53 by chain 71^a. The latter receives oscillating movement from shaft 65 by means of a cam 83 and a cam roller 84 carried by a lever 85 which is pivoted to the machine frame at 86. Lever 85, is, by a link 87, connected to one of the arms 82, so as to impart an alternating upward and downward movement to brushes 80. This movement is so timed that the brushes are gradually raised after having scrubbed the bottle necks to accommodate the bottle bodies, while the bottles are simultaneously fed underneath brushes 80 by the bottom brushes 57.

For scrubbing the interior of the bottles there is reciprocably mounted a cross head 88 in which are rotatably fitted a series of sleeves 89 arranged in the paths of bottles A, and having flaring ends 90, 91. To each end of cross head 88 is secured a chain 92 running over roller 93 and carrying a counterweight 94, weights 94 tending to draw the cross head against fixed stops 95. Head 88 is provided with rollers 96 traveling on rails 97 and with a pair of rods 98 that pass loosely through a pair of transverse beams 99 forming part of a carriage 100. At their outer ends, rods 98 pass through a corresponding sleeve 101 of an oscillating water supply pipe 102, and are headed as at 103. At each end, pipe 102 is provided with a socket 104 adapted for the reception of a gudgeon 105 formed on an arm 106 that turns on an arbor 107. Each arm 106 is, by a link 108, connected to one arm of an elbow lever 109 pivoted at 110, the other arm of which carries a roller 111

engaging the groove 112 of a cam 113 keyed to shaft 65. Opposite gudgeon 105, each arm 106 is provided with a stud 114 which is embraced by an arm 115 that operatively connects pipe 102 with carriage 100. In alignment with each sleeve 89, there is rotatably mounted in suitable bearings 116 of beams 99, a tube 117 that enters pipe 102 through a stuffing box 118. To the free ends of tubes 117 are secured the hollow stems 119 of internal brushes 120 which are adapted to be projected through sleeves 89 into the bottles to be scrubbed. Pipe 102 is, by a nipple 121 and a flexible tube, (not shown), connected to a suitable water supply, so as to introduce fresh water through tubes 117 and hollow stems 119 into the bottles while the same are internally scrubbed.

Brushes 120 are continuously rotated at high speed, so as to insure a proper internal scrubbing of the bottles, for which purpose one of the arbors 107 carries a sprocket wheel which is by chain 122 connected to a sprocket wheel 123 loosely mounted upon stud 114. Sprocket wheel 123 is made integral with a similar wheel 124, which is, by chain 125, connected to a sprocket wheel 126 keyed to a transverse spindle 127. The latter is rotatably mounted in suitable bearings 128 of carriage 100 and carries, at each end thereof, a beveled gear wheel 129 meshing into a similar wheel 130. To each wheel 130 is secured a sprocket wheel 131 which, by a train of chains 132, simultaneously rotates all of the brushes 120 toward the center of the carriage. The latter is provided with wheels 133 traveling on rails 134 which are so curved that the axes of head 88, carriage 100 and pipe 102, are always located in a common plane.

When a row of bottles is discharged from drum 17, they will be intermittently fed along rollers 49 by brushes 57, to be successively subjected to the action of rotary brushes 70, 80, so that the sides and the bottoms of the bottles are thoroughly scrubbed. After the bottles have arrived underneath brushes 80, they are temporarily arrested and carriage 100, together with pipe 102 and cross head 88, are, by arms 106 advanced toward the bottles, the movement of cross head 88 being effected by counterweights 94. When the cross head abuts against stops 95, the bottle heads are received within flaring ends 90 of sleeves 89, (Fig. 5). By the continuing advance of carriage 100, the rotating brushes 119, 120 are projected into the bottles. Owing to the undulated section 112^a, of cam groove 112, the brushes are slightly reciprocated within the bottles while water is introduced through the hollow stems 119, so that a thorough internal scrubbing of the bottles is insured. During the subsequent receding movement of carriage 100, the brushes 119, 130

120 will first be withdrawn from the bottles until head 103 is taken along by tube 102 to retract cross head 88 against the action of weights 94. Brushes 55, 56 will now be 5 again partially advanced to throw the scrubbed bottles off rollers 49, while advancing the next row of bottles underneath brushes 80. The cleaned bottles descend along a chute 135 from which they may be 10 removed in any suitable manner.

It will be seen that by the construction described, automatic means are provided for soaking the bottles and for scrubbing the interior and the exterior of the soaked bottles in a quick, effective and reliable manner.

I claim:

1. A machine of the character described, comprising a plurality of co-operating soaking drums adapted to successively receive 20 rows of bottles, automatic means for delivering the bottles from the drums to a series of rotating feed rollers, rotating external brushes adapted to engage the bottles, a series of internal brushes, automatic means 25 for projecting said internal brushes into the bottles and withdrawing them therefrom, and automatic means for removing the bottles.

2. A machine of the character described, 30 comprising a series of rotatable flared sleeves adapted to engage the bottle heads, a series of rotary internal brushes adapted to be projected through said sleeves into the bottles, and means for axially vibrating the 35 brushes within the bottles.

3. A machine of the character described; comprising a series of feed rollers adapted to support a series of bottles, external brushes adapted to engage the bottles, a cross head having a series of rotatable flared 40 sleeves which are adapted to engage the bottle heads, a fixed stop adapted to be engaged by said cross head, a carriage, a series of rotary internal brushes journaled therein and adapted to be projected through said 45 sleeves into the bottles, means for axially vibrating the internal brushes within the bottles, and means for operatively connecting the cross head to the carriage.

4. A machine of the character described, 50 comprising a series of feed rollers adapted to support a series of bottles, external brushes adapted to engage the bottles, a cross head having a series of rotatable flared sleeves which are adapted to engage the 55 bottle heads, a fixed stop adapted to be engaged by said cross head, a weight operatively connected to the cross head, a carriage, a series of rotary internal brushes journaled therein and adapted to be projected 60 through said sleeves into the bottles, means for axially vibrating the internal brushes within the bottles, means for reciprocating the carriage, and means for operatively connecting the cross head to the carriage.

JOHN A. PRINCE.
